No. 687,544.

Patented Nov. 26, 1901.

F. J. RAEHN.

BIB COCK.

(Application filed Feb. 21, 1901.)

(No Model.)

UNITED STATES PATENT OFFICE.

FRANCIS JOSEPH RAEHN, OF ALLEGHENY, PENNSYLVANIA.

BIB-COCK.

SPECIFICATION forming part of Letters Patent No. 687,544, dated November 26, 1901.

Application filed February 21, 1901. Serial No. 48,205. (No model.)

To all whom it may concern:

Be it known that I, FRANCIS JOSEPH RAEHN, a citizen of the United States of America, residing at Allegheny, in the county of Allegheny and State of Pennsylvania, have invented certain new and useful Improvements in Bib-Cocks, of which the following is a specification, reference being had therein to the accompanying drawings.

10 This invention relates to certain new and useful improvements in bib-cocks, and has for its object the provision of novel means whereby the different parts may be easily taken apart and replaced with the new parts 15 when the occasion requires; furthermore, to provide means for attaching and detaching the bib-cock without the necessity of forming a wipe-joint for such attachment.

It has been found that in the use of bib- 20 cocks such as are attached to the flow-pipe by means of wipe-joints when the valve-seat becomes worn it necessitates the removal of the body portion of the bib-cock and likewise requires the removal of the wipe-joint 25 in order to replace the bib-cock. In many instances when the valve becomes worn a new one cannot be easily substituted, as it becomes necessary to replace the same by an entirely new bib-cock.

30 All of the above-mentioned difficulties are effectually overcome by the use of my improved bib-cock; and the invention resides in the particular construction, combination, and arrangement of parts, to be hereinafter more 35 fully described, and specifically pointed out in the claim.

In describing the invention in detail reference is had to the accompanying drawings, forming a part of this specification, and where- 40 in like numerals of reference indicate corresponding parts throughout the several views, in which—

Figure 1 is a vertical sectional view of my improved bib-cock, showing the same attached 45 to the supply-pipe. Fig. 2 is a side elevation of the valve-casing. Fig. 3 is a top plan view thereof. Fig. 4 is a side elevation of the valve-casing, showing the same in another position from that illustrated in Fig. 2 of the drawings. Fig. 5 is an inverted plan view of the 50 same. Fig. 6 is a perspective view of the

same. Fig. 7 is a perspective view of the removable head.

In the drawings the reference-numeral 1 indicates the supply-pipe; 2, the wipe-joint, connecting the section of pipe 3 to the supply-pipe 1. This section of pipe 3 is exteriorly screw-threaded, as shown at 4, to receive the casing of the bib-cock 5, in which is arranged the valve-casing 6, carrying at its upper extremity the upper face 7, formed integral therewith, said face 7 having formed therein screw-threaded apertures 8 to receive the head 9, having a central opening 10 and outwardly-extending lugs 11, which are likewise formed with screw-threaded apertures 12 for the reception of screws 14, which engage the screw-threaded apertures 8 of the upper face and secure the head upon the valve-casing. The lugs 11 are adapted to fit in recesses 15, 70 formed in the upper portion of the casing.

The reference-numeral 16 indicates interior screw-threads formed in the valve-casing to receive the screw-threaded portion 17 of the valve 18, carrying the valve-stem 19, extending 75 through the opening 10 of the head.

The reference-numeral 20 indicates a valve-seat secured in the casing, against which the valve 18 operates.

The reference-numeral 21 represents an 80 opening formed in the lower portion of the valve-casing, which is adapted to register with the outlet of the bib-cock in the interior of the casing.

The reference-numeral 22 represents a 85 washer arranged over the head 9, and 23 indicates a cap, the latter being interiorly screw-threaded, as shown at 24, and is secured to the upper end of the casing 5 of the bib-cock. This cap 23 is also provided with screw- 90 threads 25 at its upper extremity to engage a jam-nut 26, the upper portion of said cap and lower face of said jam-nut being recessed, as shown at 27, to receive the packing 28.

The operation of my improved valve will be 95 readily apparent from the foregoing description, and it is thought that a further detail description is unnecessary.

In case the valve becomes worn it will be seen that the same may be easily removed 100 from the valve-casing and repaired and may then be again readily replaced to its proper

position. In order to remove the valve-casing, the parts may be easily detached and a new casing replaced when the occasion requires. When the bib-cock becomes worn, 5 the same may be easily detached from the pipe 3 and a new one inserted in its place.

It will be noted that various changes may be made in the details of construction without departing from the general spirit of my invention.

Having thus fully described my invention, what I claim as new, and desire to secure by Letters Patent, is—

In a bib-cock, the combination of a flow- 15 pipe, a section of pipe secured thereto, a removable casing, a removable valve-casing se-

cured therein, said valve-casing having an aperture formed in its lower extremity, screw-threads on its interior, said valve-casing having screw-threaded apertures formed on its 20 upper face, a head, said head being provided with outwardly-extending lugs, said lugs having screw-threaded apertures formed therein, screws for securing said head to said valve-casing, substantially as described. 25

In testimony whereof I affix my signature in the presence of two witnesses.

F. JOSEPH RAEHN.
